UNITED STATES PATENT OFFICE.

JAMES TIMMS, OF COLUMBUS, OHIO.

CAR-TRUCK.

No. 921,636.

Specification of Letters Patent. Patented May 11, 1909.

Application filed November 6, 1908. Serial No. 461,319.

To all whom it may concern:

Be it known that I, JAMES TIMMS, a citizen of the United States, residing at Columbus, in the county of Franklin and State of Ohio, 5 have invented certain new and useful Improvements in Car-Trucks, of which the following is a specification.

My invention relates to improvements in car trucks and has especial reference to the 10 construction of the truck columns, the seating of the same on the inverted arch bar, the construction of the bolster spring seat, and the provision for placing the bolster in position. The construction is such that all bolts 15 are dispensed with except at the ends of the arch bar and the inverted arch bar where the same are secured to the journal box.

It also includes other features of construction which will hereinafter be specifically set 20 forth.

In the accompanying drawings which are hereto attached and hereby made a part of this specification, Figure 1 is an elevation of a side frame with parts broken away; Fig. 2 is 25 a transverse section through the side frame with the parts in place; Fig. 3 is a perspective of a bolster; Fig. 4 is a view showing a modified form of spring seat in plan; Fig. 5 is a side view thereof.

Referring to the accompanying drawings in which the same numeral indicates the same part throughout, 1 is the arch bar resting at its ends 2 and 3 upon the journal boxes 4 and 5, and being secured thereto by means 30 of the bolts shown at 6 and 7; the arch bar has rigidly formed thereon the truck columns 8 and 9, and these columns at their lower ends are united by means of the column base 10. The notch 11 in column 9 is formed for 35 the purpose of admitting the bolster to a position in a manner hereinafter to be described. The inverted arch bar 12 is secured at its ends 13 and 14 by means of the bolts 6 and 7 to the journal boxes and to the arch 40 bar, in a manner well understood. The inverted arch bar at its center has the angular formation shown at 15, into which the column base 10 fits, being formed with the inverted arch portion shown at 16. When the 45 arches are securely positioned and fastened by means of the bolts to the journal boxes, it is seen that the angular formation of the column base engages the angular formation in the inverted arch bar, and movement of the 50 column base upon the inverted arch bar in a longitudinal direction is thereby prevented.

To accomplish this purpose, no bolts or their fastening means are needed, and the dispensing with bolts which are usually employed at this part of the car truck construction is of 60 great advantage, providing not only a stronger construction but one which is less likely to become loosened and disconnected on account of the shaking and jarring which is necessarily incident to the use of the truck. 65

The bolster 17 has the inner shoulders 18 and 19 and the outer shoulders 20 and 21 formed thereon, the portion 22 between the shoulders being formed preferably square; in positioning the bolster it is inserted through 70 the opening 23 between the truck columns until the shoulders lie upon the opposite sides of the truck columns, whereupon the portion 22 is brought into the notch 11 and the bolster is lifted to its appropriate position in the 75 upper portion of the said opening, and the inner and outer pairs of shoulders engage the truck columns on opposite sides thereof and thereby prevent any tendency of the trucks to spread. 80

The spring seat 24 is formed by using a spring plank 25, which has formed near its ends the shoulders 26 and 27, and when the plank is properly positioned as shown in Fig. 2, the shoulders extend downwardly 85 and engage the column base and the inverted arch bar on their opposite sides, and thereby prevent any tendency of the column base to shift its position laterally upon the inverted arch bar; it will be noted that this result is 90 obtained without the use of bolts, which I deem to be of great advantage. Instead of the spring plank I may employ the spring seat shown in Figs. 4 and 5, on which are formed depending shoulders or lugs 28, which 95 lie on opposite sides of the column base and inverted arch bar and lock them together. The spring is shown at 29.

In assembling the parts, the spring seat is first positioned, whereupon the bolster is 100 swung into position as described above, and the spring, under compression, is thereupon inserted between the bolster and the spring seat, resting upon the latter.

In operation, the truck frames are rigidly 105 and securely held in position with respect to each other, the column base and the inverted arch bar are securely locked against longitudinal movement relative to each other by means of the angular formation given to 110 these parts, and they are locked against lateral movement relative to each other by

means of the shoulders formed on the spring seat; one notch only need be formed, and this may be located in either of the truck columns.

5 The parts are readily assembled and disassembled, bolts are needed only at the ends of the arch bars where the latter are secured to the journal boxes, and this construction is found to have advantages both in assembling and disconnecting of the parts and in the structural locking features.

10 I do not intend to confine myself to the specific form of parts shown in the drawings, but desire to claim any variations thereof 15 which may fall within the spirit of my invention.

What I claim is:

1. In a car truck, a side frame having an arch member, truck columns and a column 20 base formed integral with said arch, the lower face of said column base having an angular formation, an inverted arch bar having an angular formation adapted to receive the angular formation of said column 25 base whereby the parts are locked together against longitudinal movement relative to each other.

2. In a car truck, a side frame comprising an arch bar, truck columns and a column 30 base formed integral therewith, one of said columns having a notch therein, an inverted arch bar constructed to engage said column base and lock the same against longitudinal 35 movement relative to said inverted arch bar, and a bolster constructed to be inserted between said truck columns and swung into proper operating position through such notch.

3. In a car truck, a side frame comprising an arch bar, truck columns and a column 40 base formed integral therewith, one of said columns having a notch therein, an inverted arch bar constructed to engage said column base and lock the same against longitudinal

movement relative to said inverted arch bar, and a bolster constructed to be inserted between said truck columns and swung into proper operating position through such notch, and a spring seat having depending extensions thereon adapted to embrace said column base and said inverted arch bar to prevent lateral movement thereof with respect to each other.

4. In a car truck, a side frame comprising an arch bar, guide columns and a column 45 base formed integral therewith, said column base having a downward projection, an inverted arch bar constructed to receive said projection and thereby lock said column base and said arch bar against lateral movement relative to each other, one of said columns having a notch therein, a bolster having spaced apart shoulders adjacent its ends adapted to be inserted between said columns and turned through said notch into proper operating position, a spring seat mounted 50 upon said column base and means upon said seat for embracing said column base and said inverted arch bar to prevent relative lateral movement thereof.

5. In a car truck, a side frame, comprising 55 two members, an extension formed upon one of said members, said other member being formed with a corresponding depression to receive said extension to lock said parts together, one of said members having an opening formed therein for receiving a bolster and spring, and a spring seat positioned in said opening adapted to embrace said members and prevent lateral relative movement 60 thereof.

6. In testimony whereof I affix my signature in the presence of two witnesses.

JAMES TIMMS.
